UNITED STATES PATENT OFFICE.

WILLIAM M. TULLEY, OF CORPUS CHRISTI, TEXAS, ASSIGNOR OF ONE-HALF TO BAILEY E. CHANEY, OF CORPUS CHRISTI, TEXAS.

PNEUMATIC COTTON PICKING AND TRANSFERRING MACHINE.

1,184,150.

Specification of Letters Patent. Patented May 23, 1916.

Application filed October 14, 1915. Serial No. 55,858.

To all whom it may concern:

Be it known that I, WILLIAM M. TULLEY, a citizen of the United States, residing at Corpus Christi, in the county of Nueces and State of Texas, have invented certain new and useful Improvements in Pneumatic Cotton Picking and Transferring Machines; and I do declare the following to be a full, clear, and exact description of the invention, such as will enable others skilled in the art to which it appertains to make and use the same.

My invention relates broadly to improvements in cotton picking machines and more particularly to those of the pneumatic type in which the cotton is drawn by suction from the plants and deposited into a receiver carried by the machine.

The object of the invention is to provide novel means whereby the cotton, after once being picked and deposited into the receiver, may be readily transferred from the latter to a wagon, whereby it may be conveyed to a gin or the like without using the picking machine for this purpose.

With this general object in view, the invention resides in certain novel features of construction and in unique combinations of parts to be hereinafter fully described and claimed, the descriptive matter being supplemented by the accompanying drawings wherein,

Figure 1 is a side elevation of a machine constructed in accordance with my invention; Fig. 2 is a top plan view thereof with parts broken away and in section; Fig. 3 is a vertical transverse section taken on the planes indicated by the line 3—3 of Fig. 1; Fig. 4 is a detail horizontal section through the suction device and parts immediately associated therewith, this view being taken on the plane of the line 4—4 of Fig. 3; Fig. 5 is a detail front elevation with the unloading tube coupled to the suction device; and Fig. 6 is a detail vertical section taken on the plane of the line 6—6 of Fig. 5.

In describing the invention, reference will be made to the accompanying drawings by similar reference characters placed on corresponding parts throughout the several views. To this end, the numeral 1 indicates a portable truck which may be drawn by tractor or horse power and thus propelled through the cotton field. Mounted on the truck 1 is any preferred type of cotton rack

or receiver 2 which is preferably provided with a sectional top 3 of wire netting or the like. Mounted on the front end of the truck 1, is a fan housing 4 from which a passageway 5 in the form of a pipe leads to the receiver 2, delivering preferably into said receiver through an opening 6 in the top thereof.

The pipe 5 is equipped with a laterally extending branch 7 whose inner end is normally closed by a gate 8 controlled at will by the lever 9, the latter being normally held against movement by appropriate locking means 10. When desired, however, the gate 8 may be swung inwardly across the pipe 5 to direct cotton in the latter through the branch 7 rather than allowing such cotton to enter the receiver 2, this being expedient for a purpose yet to appear.

As is common with devices of the class to which the invention relates, a suction fan 11 is rotated within the housing 4, being preferably driven from a gasoline engine 12 through the instrumentality of the friction drive 13 thrown into and out of action at will by the provision of an appropriate lever 14.

One side of the housing 4, in alignment with the axis of the fan 11, is provided with an outwardly extending flange or sleeve 15 which normally receives therein the connected rear ends of a plurality of cotton picking tubes 16 through which the cotton is drawn from the plants and deposited into the housing 4, it being conveyed from the latter through the pipe 5 into the receiver 2. Normally, the picking tubes 16 are held within the sleeve 15 by a set screw 17 or by any other preferred type of fastener, but it will be obvious that by loosening the set screw or other locking device, the tubes may be easily removed.

Mounted in any preferred manner, being shown in the present embodiment of the invention as extending through the front of the receiver 2 and as supported by a bracket 18 on the housing 4, is an unloading tube 19 whose rear end is disposed in the aforesaid receiver and is preferably equipped with a flexible hose or the like 20. The front end of the tube 19, on the other hand, is curved downwardly and equipped with an elbow 21 hinged thereto at 22 and normally held supported by a hook 22 or the equivalent thereof. The free end of the 110

elbow 21 is so shaped as to be received snugly in the sleeve 15, after first removing the tubes 16 therefrom. Thus it will be evident that when the receiver 2 has been filled with 5 cotton picked from the field by the tubes 16, the latter may be removed, whereupon the elbow 21 may be coupled to the inlet of the suction device, with the result that the latter will create a suction through the unloading tube 19, thus allowing the contents of 10 the aforesaid receiver to be drawn therefrom and discharged through the branch 7, the gate 8 having been previously disposed inwardly to the dotted line position shown 15 in Fig. 4. The branch 7 may either deposit directly into a wagon or the like disposed temporarily alongside of the machine, or a tube (not shown) may lead from said branch to such wagon, or to a stack in the 20 field.

From the foregoing description, taken in connection with the accompanying drawings, it will be obvious that although the construction of the machine is comparatively simple, its use will be efficient and its 25 advantages numerous.

In the drawings, certain specific details of construction have been shown for illustrative purposes, and in the preceding such 30 details have been described, but it is to be understood that numerous changes may be made within the scope of the invention as claimed, without sacrificing any of the advantages thereof.

35 I claim:—

1. In combination, a receiver, a combined suction and blast device for delivering material into said receiver or at another point, a passage member through which material 40 is to be conveyed to the aforesaid suction and blast device, a second passage member leading from the receiver, and coupling means for detachably connecting either of said passage members with the inlet of the 45 aforesaid device.

2. In combination, a receiver, a combined suction and blast device for delivering material into said receiver or at another point, a detachable passage member leading to the 50 inlet of said suction and blast device and

through which material is to be conveyed into said device, and an additional passage member leading from the receiver and adapted to be coupled to said inlet of the aforesaid device when the other passage 55 member is removed.

3. In combination, a receiver, a combined suction and blast device for delivering material into said receiver or at another point, a detachable passage member leading to the 60 inlet of said combined suction and blast device and through which material is to be conveyed into said device, and an additional passage member leading from the receiver and having a movable section and 65 adapted to be coupled to said inlet of the aforesaid device when the other passage member is detached.

4. In combination, a receiver, a combined suction and blast device for delivering material into said receiver or at another point, a detachable passage member leading to the inlet of said suction and blast device and through which material is to be conveyed 70 into said device, and an additional passage member leading from the receiver and having a laterally swinging elbow adapted to be coupled to said inlet of the aforesaid suction and blast device when the other passage 75 member is detached.

5. In combination, a receiver, a combined suction and blast device for delivering material into said receiver or at another point, a sleeve at the inlet of said suction and blast device, an inlet tube telescopically engaging 80 said sleeve, releasable fastening means for normally preventing removal of the tube, and an additional tube leading from the receiver and having a laterally swinging elbow for telescopic engagement 85 with the aforesaid sleeve when the first named tube is removed.

In testimony whereof I have hereunto set my hand in presence of two subscribing witnesses.

WILLIAM M. TULLEY.
